UNITED STATES PATENT OFFICE.

CARL DELLMANN, OF DÜSSELDORF, GERMANY, ASSIGNOR TO THE FIRM OF DÜSSELDORFER KRAHNBAUGESELLSCHAFT LIEBE - HARKORT G. M. B. H., OF DÜSSELDORF, GERMANY.

DREDGER.

SPECIFICATION forming part of Letters Patent No. 788,891, dated May 2, 1905.

Application filed September 28, 1904. Serial No. 226,368.

To all whom it may concern:

Be it known that I, CARL DELLMANN, engineer, a subject of the King of Prussia, German Emperor, and a resident of Schützenstrasse, Düsseldorf, in the Province of the Rhine, German Empire, have invented certain new and useful Improvements in Dredgers, of which the following is an exact specification.

- My invention relates to a turning-scoop dredger or self-gripper, and more especially to a new construction of the block and tackle for opening and closing the scoops. In the constructions hitherto used this block and tackle consists in most cases of two halves symmetrically arranged to the scoop middle, the chain parts of which are connected to the chain for opening and closing by means of a cross-frog. When this cross-frog runs upon the chain-roller, shocks arise, which, however, will be avoided by my present invention. For this purpose I employ a block and tackle with one chain only.

My invention consists therein that the block-and-tackle rollers being in the middle plane vertically to the direction of the scoop movement are so arranged that the first and the second vertical chain part are situated at both ends of the traverse for closing the scoops, and if further chain parts are present the same are arranged right and left hand to the gripper middle.

In order to make my invention more clear, I refer to the accompanying drawings, in which—

Figure 1 is a front view of a convenient form of my invention. Fig. 2 is a side view of the same.

In the drawings, *d* represents scoops turning around the trunnions or pivots *q*.

a is the scoop-frame.

b is a traverse moving up and down within the scoop-frame. The scoops *d* are connected to the traverse *b* by means of joint-rods *c*.

g h m l are rollers mounted upon the scoop-frame, whereas *i k n* are rollers mounted upon the traverse *b*.

f is a chain which is guided in such a man-

ner around the rollers mentioned that the first and the second vertical chain part *e* are 50 situated at both ends of the scoop. The third and fourth chain parts, however, are arranged on the right and left side to the gripper middle, as shown in the drawings.

In arrangements in which further chain 55 parts should be arranged the same would be guided in a corresponding manner. The end of the chain *f* is fastened to the scoop-frame *a* at *o*.

The closing of the scoops is effected by rack- 60 ing the chain *f*. Thereby the traverse *b* is moved upward within the frame *a*, so that the scoop ends approach each other. For opening the scoops a chain *s* is provided, which is held fast for this purpose, and then the chain *f* is 65 loosened, so that the scoop ends remove from each other by their own weight. As in my present construction of block and tackle two successive chain parts are arranged at different sides to the scoop middle, it can be ob- 70 tained that the resultant of all the chain-trac- tion forces is in the middle of the gripper, so that the traverse cannot get oblique, whereby a good working of the arrangement is ob- 75 tained, so that the apparatus cannot get out of order.

Having thus fully described the nature of my invention, what I desire to secure by Letters Patent of the United States is—

1. In a turning-scoop dredger, the combination of a frame, scoops pivotally mounted in this frame, with a traverse for closing the scoops, means for connecting the traverse to the scoops, a set of rollers mounted on the frame, a second set of rollers mounted on the 85 traverse, a chain led around the rollers and secured with one end to the frame, the rollers being so arranged in the middle plane vertical to the direction of the turning movement of the scoops, that the first and the second 90 vertical chain part are at both ends of the traverse, substantially as described and for the purpose set forth.

2. In a turning-scoop dredger, the combination of a frame, scoops pivotally mounted 95 on the frame, with a traverse for closing the

scoops, joint-rods for connecting the traverse to the scoops, a block and tackle consisting of a set of rollers mounted on the frame, and a second set of rollers mounted on the traverse, 5 a chain led around the rollers and secured with one end to the frame, the rollers being so arranged in the middle plane vertical to the direction of the turning movement of the scoops, that the first and the second vertical 10 chain part are at both ends of the traverse,

and the other chain parts are so arranged that the resultant of all the chain-traction forces is in the middle of the dredger, substantially as described and for the purpose set forth.

In witness whereof I have hereunto set my 15 hand in the presence of two witnesses.

CARL DELLMANN.
